UNITED STATES PATENT OFFICE.

HARRY E. NORWOOD AND FREDERICK G. MAIER, OF NEW YORK, N. Y., ASSIGNEES TO
PERFECT WINDOW REGULATOR COMPANY, OF NEW YORK, N. Y., A CORPORATION
OF MAINE.

WINDOW OPENING AND CLOSING MECHANISM.

Application filed June 16, 1920. Serial No. 389,277.

To all whom it may concern:

Be it known that we, HARRY E. NORWOOD and FREDERICK G. MAIER, citizens of the United States, and residents of New York, 5 in the county of New York and State of New York, have invented certain new and useful Improvements in Window Opening and Closing Mechanisms, of which the following is a specification.

10 Our invention relates to mechanism for operating windows to close or open the window opening and particularly relates to mechanism for operating double windows, that is, it relates to such cases wherein two or 15 more panes or panels of glass are employed to close a single window opening.

The invention is particularly useful in connection with the windows of automobile closed bodies although it may be applied to 20 other uses wherein it is desired to have all parts of the window travel in the same direction.

In some parts of automobile bodies as well as in some constructions of bodies the well 25 below the window opening is not of sufficient depth to permit a one part window to drop down far enough to completely clear the whole window opening from the sill to the top. Therefore when the window has 30 been dropped into the well as far as possible it still projects above the sill and prevents obtaining the advantages of the full window opening. This is the case in the partition in back of the driver's seat in most 35 limousine body constructions and also exists in many constructions in connection with the windows at the rear seats of the body and particularly when employing mechanical means for raising and lowering the windows.

40 The object of our invention is to permit the window opening to be fully exposed particularly when employing mechanical means for raising and lowering it and when the well is not deep enough to take a single window of the size of the window opening.

A further object is to reduce the time necessary to close or open the window and to effect the desired result in a simple, efficient manner.

50 A still further object is to provide a mechanism for carrying out the above objects which will be free from rattle and liability to get out of order.

In carrying out the invention the window 55 is divided longitudinally into prefer-

ably two parts and in such case in opening or closing the same, the one part travels at twice the speed of the other part so that the two parts lie alongside each other in parallel planes in the well when the window 60 opening is fully exposed.

The invention consists in the mechanism for opening and closing double windows as hereinafter more particularly described and then specified in the claims.

In the accompanying drawings:

Fig. 1 is a front elevation of a double window construction in accordance with this invention.

Fig. 2 is an enlarged vertical cross-section taken on the line 2-2 of Fig. 1 and looking in the direction of the arrows, the window being shown in fully closed position.

Fig. 3 is a view similar to Fig. 2 and showing the window in fully open position.

Fig. 4 is an enlarged transverse section taken on the line 4-4 Fig. 2.

Fig. 5 is a similar section taken on the line 5-5 Fig. 2.

Fig. 6 is a similar section taken on the line 6-6 Fig. 2.

Fig. 7 is a similar section taken on the line 7-7 Fig. 2.

For simplicity of construction and operation it is preferable to divide the window 85 horizontally into but two parts or sections and it is so shown and will be so described and when so divided the upper part or section travels at twice the speed of the other lower part but it will be understood that the 90 window may be divided into a greater number of parts all connected for operation together and in which one part may travel at a different relative speed to the other part or parts than twice the speed without departing from the spirit of this invention.

Referring to the drawings 1 and 2 indicate the usual channels secured to the frames at each side of the window opening and in which channels the window 100 travels in its movement to expose or close the window opening.

3 indicates the well into which the window drops when lowered, the well being located below the sill 4 and in back of the 105 inner partition or panel 5 (see Figs. 2 and 3).

6 and 7 indicates the panes or panels of glass comprising the double window or sections of window. These panes are located 110

in parallel planes, one forward of the other and so positioned that when in completely closed position, one part slightly overlaps the other.

5 The lower pane 7 is seated in and carried by a channel 8 to which is connected a mechanical raising and lowering mechanism of any suitable kind and typified at 9 which is located in the well below the 10 window and usually in a well in the door and below the window opening. Mechanical means for raising and lowering the windows of automobile bodies are now 15 universally employed and their mode of operation is well understood by those skilled in the art. A construction of such mechanism suitable for use with our invention is shown and described in United States Patent No. 1,218,130, dated March 6th, 1917 20 and, as well understood in the art, upon rotating the operating handle, which is connected with the sprocket 12, in one direction or the other the lower pane 7 or lower section of the window will be raised or lowered 25 as the case may be due to the pin 10 working in the slot 11 of the plate 13, said plate being connected with the channel 8.

At each side of the windows 6 and 7 and located in the channels 1 and 2 the mechanism connecting the window panes or sections of window together is located. For the purpose of sustaining or providing means for attachment of the mechanism to the upper section of the window, an angle strip 14 30 may be cemented to each vertical edge of the upper pane or section 6 and similarly a channel strip 15 may be cemented or secured to each vertical edge of the lower section or lower pane 7. Each strip 14 carries at its 35 lower end a block 16 in which a lug or pin 17 or other device is mounted for the attachment of a suitable cable or rope preferably of metal, employed as will be presently described. Mounted upon each strip 15 of the 40 lower section and at or near the upper edge of the section is a pulley 18 and on each strip at or near the lower end thereof is similarly mounted a pulley 19.

20 indicates wire cable which may be 50 endless but which, operatively considered, comprises two sections. A similar section is provided at each edge or side of the lower section of the window. A section of cable at one side of the lower section is attached at one end to a block 21 suitably fastened to the sill 4 of the door or casing in which the window receiving well is located. The other end of said section of rope passes over the upper pulley 18 on the 55 same side of the window and extends downwardly for attachment to the pin or lug 17 on the same side of the window. Another section of cable is similarly connected at the opposite edge or side of the lower sec-

tion to the block 21 at one end and at the 65 other to a pin or lug 17 and is carried over a similar pulley 18. Another section of cord attached to the block 21 or to other suitable fixture passes down and around the pulley 19 at the lower edge of the lower 70 section and then up for attachment to the lower edge of the upper section of window by means of the projecting pin or lug 17 or other device. A similar section of cord is similarly connected and passes over a 75 pulley in a similar way at the opposite edge.

In the operation of the device, upon actuating the mechanism 9, the lower pane 7 is moved up or down due to its connection therewith. This travel of the pane 7, carrying the pulleys 18 and 19 with it, causes a corresponding travel of the pane 6 in the same direction due to the connection with the cable 20, the cable being fixed by its connection 21 and being sustained in any 85 desired lifting position by the means usually employed in the art.

When the lower section is lowered by the operation of the mechanism 9, the upper section is lowered at twice the speed by the 90 operation of the two movable pulleys 19 which move with the lower section and have sections of cable, each attached at one end, running over them and attached at one end to the sill 21 and at the other end to the 95 lower rail or edge of the upper section.

Thus by the time the pane 7 has been dropped completely into the well 3 the pane 6 is also completely in the well and substantially flush with the pane 7 as indicated in 100 Fig. 3. When the lower section is raised by the action of the two pulleys 18 upon the two sections of cord or cable which are attached at one end to the fixture 21 and 105 pass up and over the pulleys 18, and then down for connection with the attachment 17 at the lower edge of the upper section. This movement, obviously, owing to the action of the movable pulleys 18, produces movement 110 of the upper section at double the speed of the lower, so that when the pane 7 has been completely raised, the pane 6 or upper section will have closed the upper part of the window opening.

In this way the well 3 need only be of sufficient depth to take a window half the size of the window opening and also the speed of opening and closing the window is greatly increased over those cases where a 120 single window is employed to close the entire window opening. It will be seen that the upper section or pane 6 is at all times sustained by the lower section and that the position of rest of the latter which is determined by the raising mechanism 9 or by any suitable means, will determine the extent of the adjusted window opening above the 125

upper edge of the pane 6. Also, it will be seen that the upper section being sustained at both edges, it is not liable to bind in the channels.

5 What we claim as our invention is:—

1. In a double operating mechanism, for windows divided horizontally into two sections the combination with means for raising and lowering the lower section, pulleys

10 secured to said section near its upper horizontal edge and a cable passing around said pulleys and connected with and sustaining the other section whereby upon imparting movement to the first section the second will

15 travel in the same direction at double the speed and will be sustained by the lower section in any adjusted position thereof.

2. In a window operating mechanism, a plurality of windows for a single window opening, means for raising and lowering connected to the lower window, pulleys carried by said window near its upper edge and also near its lower edge and a cable secured at a fixed point and passing around 25 said pulleys, said cable being secured to the upper window whereby upon movement of the first window the other window will travel in the same direction but at a different relative speed and will be sustained by said lower window in all adjusted positions thereof.

3. In a double window operating mechanism, for a window divided horizontally into sections raising and lowering means 35 connected to one window, pulleys carried by said window, at or near its upper edge and at both sides thereof, sections of a cable secured to the window sill and passing around said pulleys and a stud connecting

40 the other window at each side near its lower edge to said sections of cable as and for the purpose described.

4. In a window operating mechanism, a plurality of windows for a single window

opening, mechanical raising and lowering 45 means connected to the lower window in the well below the window opening, pulleys secured to the top and bottom of said window at each side thereof and a cable passing over said pulleys at each side of the window, 50 each cable being anchored at a fixed point and attached at a different point to the upper window and serve to sustain the upper window as well as operating it in both directions, whereby, upon operating said 55 means, all the windows will travel in the same direction but at relatively different speeds.

5. A window operating mechanism for carriage windows comprising two sections 60 having an actuating mechanism connected with and operating upon the lower section to raise and lower the same, pulleys attached to both edges of the lower section near the top thereof as well as near the bottom, sections of cable fixed at one end to the window frame and passing up and over the upper pulleys and down for attachment to the lower edge of the upper section, other sections of cable fixed to said window frame 65 and passing down around the pulleys at the lower edge of the lower section and up for attachment to the lower edge of the upper section and means within the well below the window opening for operating the lower 75 section to raise and lower both sections while at the same time sustaining the upper section from the lower, all of said parts being fully housed within the well when both sections are fully lowered.

Signed at New York in the county of New York and State of New York this 15th day of June, A. D. 1920.

HARRY E. NORWOOD.
FREDERICK G. MAIER.
